JARRING APPARATUS FOR PACKING GRANULAR MATERIALS.

1,102,367.

Specification of Letters Patent.

Patented July 7, 1914.

Application filed June 17, 1912. Serial No. 704,092.

To all whom it may concern:

Be it known that I, HENRY TSCHERNING, a citizen of the United States, residing at Freeport, in the county of Stephenson and State of Illinois, have invented certain new and useful Improvements in Jarring Apparatus for Packing Granular Materials, of which the following is a specification, reference being had therein to the accompanying drawing.

This invention relates to jarring and thereby packing granular material and the apparatus embodying the invention and shown in the accompanying drawings is especially adapted for packing molding sand about the patterns in molding flasks, the flask being raised by compressed air or the like, released, and then abruptly arrested in its falling movement.

In the accompanying drawings, Figure 1 shows my devices partly in side elevation, partly in section, the plane of section being indicated on Fig. 2 by the line 1—1, Fig. 2 is a section on the line 2—2, Fig. 1, and Fig. 3 is a section on the line 3—3, Fig. 2. Fig. 4 is a section on the line 4—4, Fig. 3.

In these figures, A represents a strong cylinder having a base A' and heavy external ribs A² extending to its open upper end. In the cylinder wall is formed an inlet passage A³ opening outwardly at some distance above the base and inwardly at the bottom of the cylinder. In the lower part of the cylinder is a curved chamber A⁴ communicating with the interior of the cylinder by a circumferential slot, as indicated by dotted lines in Fig. 2, and with an exhaust pipe A⁵. In the cylinder works a piston B provided at its upper end with a broad and heavy flange B' normally resting upon the upper ends of the ribs, the actual contact being made by a renewable ring B², or the like, lying in a recess in the lower face of the flange proper. The piston supports a molding table B³ upon which the molding flask is placed. At the lower end of the piston is a plate B⁴ which is freely movable vertically on the shaft of a central vertical screw B⁵ working in the lower end of the piston. This plate is provided with vertical perforations B⁶ and with a peripheral groove in which is loosely seated an internal rib B⁷ on a broken ring B⁸ of spring metal which by its resiliency always presses against the cylinder wall with such force as to resist gravity and which covers the outlet to the

chamber A⁴. All the parts at the lower end of the piston are so placed that they do not prevent the piston flange from resting upon the cylinder ribs.

The piston is actuated by compressed air, or the like, brought from any convenient source by a pipe C provided with a hand valve C' and leading to automatic valve mechanism in a casing D upon the cylinder A. This casing contains two chambers D', D² into which, respectively, lead passages D³, D⁴ from the pipe C. The chambers D' and D² are connected at top and bottom by passages D⁵, D⁶, and the casing is further provided, in this instance at a point directly opposite the passage D⁴ with a channel D⁷ in open communication with the passage A³ in the walls of the cylinder A. In the cylinder D' slides a heavy free piston E having a central, circumferential groove E', the arrangement being such that when this piston is at its lowest point, where its weight normally holds it, the passage D⁴ is closed and the ports of D⁵, D⁶ are uncovered, while if the piston is raised to its highest point the passage D⁴ communicates with the groove E' and through it with the channel D⁷. In the cylindrical chamber D² works a piston valve F, always urged toward its highest position by a spring F' and having a stem F² projecting through the top of the casing and provided with a shoulder F³ which limits its upward movement. This valve is centrally diminished to form an annular chamber F⁴ into which the passage D³ opens. Upon the upper end of the piston valve stem normally rests an adjustable rod B¹⁰ projecting downward from the flange B', and the length of the rod is such that when the flange rests upon the ribs of the main cylinder, the weight of the parts holds the spring F' compressed and keeps the piston valve depressed so that the flow of fluid from the chamber F⁴ to the passage D⁶ is prevented, while the passages D³ and D⁶ are both open and in communication.

If the hand valve V' be opened, compressed fluid passes through the passage D³ (D⁴ being closed by the piston E) into the valve recess F⁴, and thence through the passage D⁶ into the cylinder D' where it raises the piston E, bringing the passage E' into registry with the passages D⁴, D⁷ and thus allowing the fluid to pass through the channel A³ to the interior of the cylinder A, and through the perforations in the plate B⁴, and

into the narrow chamber between the piston and the plate B⁴, which is always held away from the body of the piston by suitable projections B¹¹. As this piston begins to rise it withdraws from the plate but after it has ascended through a short distance, the head of the screw picks up the plate and this as it rises picks up the ring B⁸ and thus uncovers the exhaust slot allowing sudden discharge 10 into the circular chamber and a slower discharge through the pipe A⁵. When this occurs, the piston and flask table fall until they are suddenly arrested by the impact of the piston flange upon the ribs of the cylinder. 15 But as soon as the main piston rises, the spring F' forces the valve F to follow, cutting off the actuating fluid from the passage D⁶, opening this passage to the exhaust passages Q, and then opening the passage D⁵ to 20 the actuating fluid so that the latter may enter the space above the piston E, and thus the latter is restored to initial position. But the falling of the main piston and its flange pushes the valve F again downward, against 25 the force of the spring, and thereby opens the passage D⁵ to the exhaust Q' and again admits fluid to the passage D⁶. This cycle of operations is repeated rapidly and indefinitely so long as the valve C' is allowed to 30 remain open.

The distance through which the piston falls may obviously be made as great or small as desired, and by placing the distinct impact member outside the cylinder wear 35 may be readily observed and compensated. By having the impact at several points the blow is divided, by impact beneath widely separated points of the table, the work is better done, and by having the impact at the 40 upper end of the cylinder on heavy vertically continuous metal extending to the base, a better effect is obtained for a given weight of the cylinder.

What I claim is:

1. In apparatus of the class described, the combination with an upright cylinder having below an inlet port and an exhaust port, of a jarring piston arranged for reciprocating in said cylinder and provided with a 50 lateral projection to engage the cylinder and abruptly arrest the downward movement of the piston before it reaches the bottom of the cylinder, an independently movable member carried by the piston for closing and opening the exhaust port, and automatic devices operating in time with the piston to admit actuating fluid through said inlet port.

2. The combination with a vertical cylinder provided with an inlet port, with a circumferential chamber communicating with the interior of the cylinder through a broad circumferential slot and with an outwardly extending exhaust passage, of a piston ar-

ranged to open and close said slot in reciprocating, and automatic means for supplying 65 actuating fluid intermittently through said inlet port.

3. The combination with a cylinder provided below with inlet and exhaust ports, of a piston working in the cylinder and having 70 at its upper end above the cylinder an external flange in position to keep the piston above the bottom of the cylinder, a plate below the piston, carried thereby, and capable of limited independent vertical movement, 75 an exhaust-controlling spring ring carried by the plate and adapted to support its own weight and that of the plate by frictional engagement with the interior of the cylinder, and automatic means for intermittently admitting fluid under pressure at said inlet port.

4. The combination with a cylinder having below inlet and exhaust ports, of a piston working in the cylinder, independently movable means carried by the piston for opening and closing the exhaust port, automatic valve mechanism for securing admission of actuating fluid intermittently in time with the piston movements, and manually operated 90 means for arresting the movements of the valve mechanism.

5. The combination with a cylinder having below inlet and exhaust ports, of a jarring piston working in the cylinder, means 95 within the cylinder whereby the piston alternately opens and closes the exhaust, an external valve mechanism, allowing operating fluid to pass to the inlet periodically, comprising a reciprocating valve governing the 100 inlet passage and a second valve normally allowing fluid to pass to the first valve, and means whereby rising of the piston causes the shifting of both valves cutting off the fluid, while the descent of the piston again 105 shifts both valves to initial position.

6. The combination with a cylinder having inlet and exhaust ports below, of a piston carrying at its lower end an independently movable member for opening and closing the 110 exhaust, a reciprocating valve actuated by the motor fluid and controlling the admission of the latter to the cylinder, a second reciprocating valve controlling the supply 115 of fluid to the first valve, piston operated means whereby the second valve is held open while the piston is at and near the lower limit of its path, and a spring urging the second valve toward closed position.

In testimony whereof I affix my signature 120 in presence of two witnesses.

HENRY TSCHERNING.
